(57) **CLAIM**

The ornamental design for an adapter plate for fuel tank, as shown and described.

DESCRIPTION

FIG. 1 is an isometric view of the adapter plate, showing my new design;

FIG. 2 is a top plan view thereof;

FIG. 3 is a right side elevational view thereof, the left side elevational view being a mirror image thereof;

FIG. 4 is a front elevational view of the adapter plate thereof;

FIG. 5 is a rear elevational view of the adapter plate thereof;

and,

FIG. 6 is a bottom plan view thereof.
